UNITED STATES PATENT OFFICE.

ROBERT D. HICKOK, OF ATLANTA, GEORGIA.

ELECTRIC CLOCK.

No. 904,128.

Specification of Letters Patent.

Patented Nov. 17, 1908.

Application filed March 27, 1908. Serial No. 423,678.

To all whom it may concern:

Be it known that I, ROBERT D. HICKOK, a citizen of the United States, residing at Atlanta, in the county of Fulton and State of Georgia, have invented certain new and useful Improvements in Electric Clocks, of which the following is a specification.

This invention relates to electric clocks in which impulses are given to the pendulum by means of electro magnets which are periodically energized, and the object of the invention is to form an improved mechanism for closing the circuit and actuating the electro magnets when the pendulum vibrations fall to a predetermined minimum. The advantage of this type of apparatus is that the current is only used when it becomes necessary, to continue the vibrations of the pendulum.

20 The invention is illustrated in the accompanying drawings, in which

Figure 1 is an elevation showing the circuit closing devices in one position. Fig. 2 is a similar view with the said devices in different position. Fig. 3 is a detail in side or edge view of the parts. Fig. 4 is a section on the line 4—4, looking down. Figs. 5 and 6 are enlarged details showing a pendant and a pin which is caught thereby at the minimum vibration.

Referring specifically to the drawings, O indicates the pendulum rod with a slot N into which a pin M projects from the lower bar of a frame P the upper ends of which are connected to the armature V which is pivoted at v to vibrate between the poles X and W of the electro magnets x and w. One side or arm of the frame P has secured thereto, on its inner edge, a flat spring D, attached by a screw Q. An adjustable screw E passes through the frame and presses against the inner or rear side of the spring. At the lower end the spring carries a block with a forwardly projecting pin C; and the screw E may be adjusted to move the spring, and consequently the pin, to the right or left, to bring the clock "in beat".

G indicates a circular bridge or bearing support in which is mounted for vibration an arbor T which carries an arm F which stops against a shoulder f on the bridge, and which causes its position at rest to be as shown in Fig. 1. From the arm F is suspended, by a pivot a, an inverted V-shaped pendant A. This is pivoted at the top, at

the angle, and the two arms balance each other. It is preferably made of aluminum for the sake of lightness. The lower end of one arm of the pendant has a projecting piece B which is notched or grooved on the under side, producing an inverted V-shape in cross section. This piece is made of hardened steel, and protrudes, say, about three millimeters back from the pendant A. The arbor T also carries a flat spring H which projects on the opposite side of the arbor from the arm F, and is conveniently fixed to the arm and the arbor by screws h. The spring H is insulated from the arm and the arbor by a strip of mica h¹ thereunder and by insulating bushings around the screws. The wire L forming one side of the circuit to the electro magnets is connected to said spring H, and the wire K on the other side of the circuit terminates in a screw J properly positioned to receive the contact of the outer end of the spring H. All of the parts described are suitably supported on the back plate S of the movement.

In operation, the pendulum rod O and the frame P oscillate together, by reason of the connection at the pin M, and the pin C swings with the frame. The parts are so arranged that the pin will strike the V-shaped piece B as the parts vibrate. On the vibration from left to right the pin will strike and lift said piece and will pass under and beyond the same, and on the return beat from right to left will again strike the inclined side of said piece and swing the same down and pass thereover. The spring H is normally out of contact with the screw J, and consequently no current is transmitted. When the pendulum reaches the predetermined point of minimum vibration the pin C will not pass the piece B, but at the end of the beat will stop directly thereunder, after lifting the same, and said piece will immediately drop, engaging the pin in the groove or V-shaped recess on the under side thereof. The pendulum then starts to swing to the left carrying with it the piece B and the pendant A until their paths diverge, and in consequence of the shorter radius of the pendant A the effect is to lift said pendant, and the arm F, as shown in Fig. 2, thereby turning the arbor T to an extent sufficient to press the spring H against the contact point J, whereby the circuit is closed and the impulse is imparted to the armature by means

of the electro magnets. As soon, then, as the pendulum swings to the left an amount equal to the minimum motion to the right, the pin C leaves the piece B and the parts 5 resume their normal position and operation until the minimum oscillation is again reached, when the operation for closing the circuit is repeated. To resume, the normal arc of vibration of the pendulum causes the 10 pin C to pass beyond the piece B, and continues to do so until the vibration falls to its minimum at which point the engagement between the pin and the pendant is effected in the manner above described and the circuit 15 is thereupon closed. The pin C, being carried by the spring D, allows it to be adjusted to the right or left, thus allowing the clock to be put exactly in beat. The use of the spring D also prevents the breakage of the pin C 20 if at any time said pin should catch upon said piece B when the pendulum is traveling to the right. It is evident that if the pin C were rigidly held and should catch as stated, either the pin or the pivot of the pendant 25 A would receive the full momentum of the pendulum and would therefore be broken.

A minimum amount of power is required to operate the device for the following reasons: first, because the only parts of the 30 device in motion—when not making contact—are the pendant A and the pin C, and said pendant being made of aluminum or other light metal and delicately balanced, with jeweled pivots if desired, a minimum 35 amount of power is required to operate it; second, because at those vibrations at which contact is made the power required to lift the arm F and swing the spring H down to contact is in fact only that needed to 40 overcome the friction of the pivots and the inertia of the parts, for the arm F is lifted to its highest position during the first half of the motion of the pendulum to the left, and returns to its original position during 45 the last half of the motion to the left, and as it returns to its original position it necessarily gives its weight to the pendulum; or in other words, the power required to lift the arm F during the first half of the 50 motion to the left is returned to the pendulum during the last half of the motion to the left. The engagement between the pin and the grooved piece, when the pendulum reaches the minimum beat, is quite certain, 55 because they are presented to or toward each other in horizontal position and because of the wide place of engagement thus provided, slight variation in the plane of oscillation is not apt to cause them to miss engagement and thus fail to close the circuit. 60

I claim:

1. In an electric clock, the combination with the pendulum rod, of an armature frame which is connected thereto and swings therewith, an adjustable spring carried by 65 the armature frame and having a projection, and means actuated by said projection to close the clock circuit at a predetermined minimum swing of the pendulum.

2. In an electric clock, the combination of 70 a pivoted arm, a circuit closing contact spring carried thereby; a pendant hanging from the arm, and means actuated by the pendulum of the clock on minimum swing thereof to engage and lift the pendant and 75 turn the arm and the spring to close the circuit.

3. In an electric clock the combination with a swinging pendant having a horizontal piece projecting therefrom with a groove in 80 its under side, of a frame vibrating with the pendulum and having a horizontal pin arranged to strike said piece and swing the pendant as the pendulum vibrates, and constructed to engage in said groove on minimum vibration, and means actuated by the pendant when so engaged to close the clock 85 circuit.

4. In an electric clock the combination of a swinging pendant having depending 90 branches at an angle to each other, one branch having a horizontal piece with a groove in its under side, a frame oscillating with the pendulum and having a horizontal pin projecting therefrom, said piece and 95 pin having intersecting arcs of oscillation, whereby the pin will strike the piece and swing the pendant, the pin being engageable in the groove on minimum oscillation of the pendulum, and means actuated by the pendant, when the pin is so engaged, to close the clock circuit. 100

5. In an electric clock the combination of a pivoted arm arranged to swing vertically and having a projecting contact spring, a 105 pendant consisting of an inverted V-shaped piece pivoted at its apex to the free end of the arm, and having a horizontal grooved piece projecting laterally from one branch thereof, a swinging frame oscillating with 110 the pendulum, and a pin projecting from the frame and arranged to strike and swing the pendant and to engage in the said groove on minimum oscillation of the frame.

In testimony whereof I affix my signature, 115 in presence of two witnesses.

ROBERT D. HICKOK.
